FOOTWEAR AND METHOD OF MAKING
SAME

John E. Taber, South Bend, Ind., assignor to
Mishawaka Rubber and Woolen Manufacturing Company, Mishawaka, Ind., a corporation
of Indiana

Application August 21, 1931. Serial No. 558,547

8 Claims. (Cl. 36—4)

My invention relates to rubber footwear where-
in an expansible portion is provided to permit
inserting and removing the foot and has refer-
ence more particularly to the construction of
5 this expansible portion.

The principal objects of my invention are:—
to provide an improved expansible portion for
rubber footwear of the form fitting type; to
construct this expansible portion as a separate
10 unit which is applied on and vulcanized to the
assembled upper of a boot, overshoe or the like;
to provide an improved lining arrangement which
may be conveniently employed in connection with
this expansion structure; to construct the upper
15 with a portion of the facing cut out to expose
the lining for application of the pocket portion
of the expansion unit thereon; to provide an
expansion structure which may be advantageously
employed in constructing a high top boot of
20 form fitting type; and in general to provide a
simple, convenient and serviceable expansion ar-
rangement which insures a neat close fitting
waterproof boot or overshoe.

25 On the drawing in which I have, for the pur-
pose of illustration, shown my invention in con-
nection with a high top rubber boot, although
it is not necessarily limited to that particular
type of rubber footwear:—

30 Fig. 1 is a perspective view of a rubber boot
constructed in accordance with my invention;

Fig. 2 is a perspective view of the lower portion
of the last with the boot lining assembled
thereon;

35 Fig. 3 is a similar view showing the boot upper
further assembled and ready for the expansion
pocket unit to be applied thereon;

Fig. 4 is a front view of the assembled pocket
40 unit with portions broken away to show details
of the construction;

Fig. 5 is a back view of the pocket unit with
portions thereof likewise broken away; and

Fig. 6 is an enlarged fragmentary sectional view
on the line 6—6 of Fig. 1.

45 Referring to the drawing, the reference nu-
meral 1 indicates the last upon which the boot is
assembled, the upper portion of the last being
broken away in Figs. 2 and 3. The lining is first
50 assembled on this last, and preferably consists
of a one piece upper portion 2 which is drawn
around the last and has the edges joined to-
gether down the back, the bottom edges of this
lining being lasted over an insole (not shown) in
55 the usual manner. A toe and vamp covering
portion 3 of lining is then arranged over the
toe and vamp portion of the last so as to overlap

the forward edge of the lining portion 2 to which
it is cemented, and the bottom edges of this toe
and vamp lining 3 are also lasted over the insole.

A one piece rubber covering 4 is then applied
around the last, cemented to the lining and joined
60 together at the back, said rubber covering being
formed with an opening part way up the front
with inwardly extending strap like portions 5 at
the bottom of this opening which are joined to-
gether over the instep as indicated at 6 so as
65 to form an elongated closed opening 7 in the
front of the rubber covering 4 which extends
upwardly from a point just above the bottom
of the instep to a point well above the ankle,
substantially as shown in Fig. 3, and exposes a
70 corresponding area of the lining to which the
back wall of the expansion pocket unit is sub-
sequently applied.

A toe covering 8 of rubber is then cemented
onto the toe and lower vamp portion of the lin-
ing and adhesively secured in overlapping re-
lation to the forward edge of the rubber cover-
ing 4, as shown in Fig. 3, and the lower edges
of both rubber coverings 4 and 8 are also lasted
over the insole. After this is completed a stitch
75 wheel is run along the lateral edges of the open-
ing 7 to partially cut through the lining imme-
diately inside these edges, but these lines of par-
tial severance, which are provided to permit the
intermediate portion of the lining to be subse-
80 quently torn apart along the edges, do not ex-
tend entirely to the upper and lower ends of
the opening 7 but are terminated at a distance
therefrom, substantially at the points A and B
85 of Fig. 3, to leave the said intermediate portion
of the lining securely attached at its upper and
lower ends to the rest of the lining. This par-
tial cutting of the aforesaid intermediate por-
tion from the rest of the lining, may of course
90 be provided before the rubber coverings 4 and 8
are applied, the line of partial severance at one
95 side of the intermediate portion of the lining
being indicated at 9 in Fig. 2.

The expansion unit is then applied to this as-
sembled structure, said unit being prepared in
the manner shown in Figs. 4 and 5. This unit
comprises a back wall 10 of rubber composition,
of a shape corresponding to but of a size smaller
than the opening 7 of the assembled upper ex-
cept at the lower end where it is provided with
an extension 11 which projects down over the
vamp covering 8, and this unit has a front wall
100 of two parts, which in the assembled unit are
joined together along their inner edges and
105

110

adapted to be separated upon completion of the boot to form the side flaps 12 and 13 thereof.

This front wall comprises a pair of side members 14 and 15 of rubber composition which are laid together edge to edge along the line 16 of Fig. 5 and joined together by the fabric tape 17, the latter having a rubber tape 18 somewhat wider than the tape 17, laid thereover, and on the outer side of each side member 14 and 15 10 a reinforcing 19 and 20 respectively is adhesively secured thereto, these fabric members, however, being narrower than the respective rubber members 14 and 15 and arranged so that their inner edges are spaced outwardly a substantial 15 distance from the inner edges of the rubber layers 14 and 15.

The members 14, 19 and 15, 20 which are flared at their lower ends to correspond to the flared formations 21 and 22 of the lower ends of the 20 boot flaps 12 and 13, are joined along their outer edges and at the top to the corresponding edges of the rubber composition back wall 10 to form an expansion pocket, the back wall 10 preferably being smaller than the assembled front wall 14—15 as shown in Figs. 5 and 6 so that the edges of the front wall 14—15 project outwardly beyond the corresponding edges of the back wall 10. In the lower end of this pocket member a reinforcing 23 of rubber composition is adhesively 30 secured to the front of the back wall 10 with a portion 24 extending downwardly over and projecting beyond the extension 11 of the wall 10, and this reinforcing 23 has side portions 25 folded inwardly along the junctures of the walls 14 and 15 with the wall 10 and adhesively secured to the under sides of the walls 14 and 15.

Each of the flap portions 12 and 13 of the boot is made up as a part of the expansion unit and subsequently applied with this unit onto the assembled boot structure of Fig. 3, the flap 12 being composed of a layer 26 of fabric which is secured along the inner edge to the rubber layer 14 at a distance from the inner edge of the latter as shown in Fig. 6 and this layer 26 of fabric 45 has another layer 27 of fabric secured thereon which extends nearly to the inner edge of the rubber layer 14 and on this fabric 27 is an outer layer 28 of rubber which extends to the inner edge of the rubber layer 14.

The outer edge of the fabric 26 extends well 50 beyond the outer edge of the rubber part 14 and the outer edge of the fabric 27 extends beyond the outer edge of the fabric 26 while the rubber 28 extends beyond the edge of the fabric 27, all 55 as shown in Fig. 5 so that the edge of the composite flap member 26, 27, 28 is of a somewhat feathered form. The other flap member 13 is made up in like manner of fabrics 29 and 30 and outer rubber layer 31, the flap members 12 and 60 13 being preferably provided with fullness at the sides to permit these flap members to readily conform to the shape of the boot wall.

After the expansion unit has been prepared in the manner above described, the back wall 10 65 of the pocket member and the edge portions of the front wall 14—15 which project around the back wall 10 are cemented to the exposed portion of the lining in the opening 7 (See Fig. 3) and the lining extension 11, 24 of the pocket 70 member is cemented onto the overlapped ends 5 of the rubber covering 4 and onto the upper portion of the rubber toe covering 8, a narrow width of exposed lining being left along each side of the pocket member substantially where 75 the lining is partially severed at 9, this exposed

width being provided to separate the pocket member along the lateral edges from the corresponding portions of the rubber covering 4 along the opening 7 and thereby avoid consolidation of the rubber of the pocket member with the rubber covering 4 along the lines of severance. 80

After the back wall of the expansion pocket has been cemented to the lining the outer edges of the flaps 12 and 13 are cemented to the rubber covering 4 along the outer sides of the respective lines of severance 9 and the joined top ends of these flaps likewise cemented to the rubber 4 and all rolled down firmly in place, thereby assembling the expansion unit onto the assembled boot upper. 85

An outer toe covering 32 is then cemented onto the toe portion of the assembled boot and is provided with a pointed portion 33 which extends up between the flared lower extremities of the flaps 12 and 13 and also has side portions 34 which extend back along the sides of the foot portions of the boot. An outer heel covering 35 is also cemented in place with side portions overlapping the rear ends of the side portions 34 of the toe covering 32, and the side portions of both the heel and toe coverings preferably overlap the lower portions of the flaps 12 and 13 substantially 95 as shown by the dotted lines at 36 in Fig. 1.

After the boot has been assembled as above described, the sole and heel are finished up in the usual manner, after which the boot is vulcanized. After vulcanization the tapes 17 and 18 which 105 connect the flaps 12 and 13 are slit so that said flaps can be separated, after which, by pulling on the flaps 12 and 13 and the inside of the expansion pocket member, the lining is torn along the lines 9 so that the expansion pocket member 110 may be expanded and the boot removed from the last.

Any desired fasteners may be employed for 115 fastening the flaps 12 and 13 together, a lacing 37 being shown in the present case. If the lacing 120 is to be employed, eyelets 38 are provided at suitable intervals along the flaps 12 and 13 as shown. 125

While I have shown and described my invention in a preferred form, I am aware that various changes and modifications may be made therein without departing from the principles of my invention, the scope of which is to be determined by the appended claims. 130

I claim as my invention:

1. In an article of rubber footwear the combination of an upper having a cut out area at the front, an expansion pocket member located in and of an area to be contained within the cut out area, and a pair of opposed laterally extending wings joined along their inner edges to the front of the expansion pocket member and vulcanized along their outer edges to the upper at the outer sides of said cut out area. 135

2. In an article of rubber foot wear the combination of an upper having a lining of fabric and a facing of rubber, the fabric having a portion thereof partially severed at the front and the rubber facing being omitted over the said partially severed portion of the lining fabric, and an expansion pocket member having a back wall secured to said partially severed portion of the lining and a front wall of separable sections secured along their outer edges to the outer edges of the back wall, and a pair of opposed laterally extending wings joined along their inner edges to the respective inner edges of the separable sections of the front wall of the expansion pocket mem- 140 145 150

- ber, and the outer edges of said wings being vulcanized to the rubber facing of the upper around the aforesaid partially severed portion of the lining fabric.
5. 3. In an article of rubber footwear the combination of an upper having a fabric lining and a rubber facing, the said lining having an elongated integral portion thereof at the front severed along laterally spaced lines from the portions of the lining at each side thereof and the rubber facing being omitted over said elongated integral portion of the lining, and an expansion pocket member having a rubber composition back wall secured to said elongated lining portion and having a rubber front wall of separable sections secured along their outer edges to the outer edges of said back wall, and a pair of opposed laterally extending wings of fabric reinforced rubber joined along their inner edges to the separable sections of said front wall and the outer edges of said wings being vulcanized to the rubber facing beyond the lateral edges of said elongated portion of the fabric lining.
25. 4. In a rubber boot the combination of a fabric lining, a rubber facing extending around and omitted over an elongated portion of the lining at the ankle and instep, and an expansion pocket member secured to said elongated portion of the lining and having mounting means thereon vulcanized to the rubber facing around said elongated portion of the lining.
30. 5. The method of making rubber footwear which includes assembling on a last a form fitting upper having a fabric lining and an outer facing layer of rubber, applying an expansion pocket member to the front of the assembled
- upper, and vulcanizing the outer edges of wing members on the front of said expansion pocket member externally to the rubber facing of the upper beyond the lateral edges of the expansion pocket member.
80. 6. The method of making rubber footwear which includes forming an expansion pocket member with a pair of opposed laterally extending wing members on the front, assembling on a last a form fitting upper having a fabric lining and an outer facing layer of rubber, then applying the expansion pocket member to the exterior of the assembled upper at the front, and then vulcanizing the outer edges of the wing members to the exterior of the rubber facing of the upper.
85. 7. The method of making rubber footwear which includes providing the upper on the last with a cut out area at the front, then applying in the cut out area an expansion pocket member of an area to be contained within the cut out area, and vulcanizing to the upper at each side of the cut out area the outer marginal edges of a pair of laterally extending wings that are attached along their inner edges to the front of the pocket member.
90. 8. The method of making a rubber boot with an expansible portion at the ankle and instep, which includes assembling the fabric lining and rubber facing of the boot upper on a last with a portion of the upper omitted from an area along the ankle and instep, then applying to said area an expansion pocket member with a pair of opposed laterally extending wings, and then vulcanizing the outer edges of said wings to the rubber facing at opposite sides of said area.
